RING TOSS GAME TARGET

Lawrence Jonesi, Chicago, Ill.

Application February 24, 1954, Serial No. 29,199

Term of patent 14 years

(Cl. D34—5)

To all whom it may concern:

Be it known that I, Lawrence Jonesi, a citizen of the United States, residing in the city of Chicago, in the county of Cook and State of Illinois, have invented a new, original, and ornamental Design for a Ring Toss Game Target, of which the following is a specification, reference being had to the accompanying drawing, forming a part thereof.

The single figure is a front elevational view of a ring toss game target, showing my new design.

The paddle is of conventional thickness, and the appearance of the back thereof, not shown, is plain or conventional.

The dominant features of my new design are shown in solid lines in the drawing.

I claim:
The ornamental design for a ring toss game target, as shown and described.
